6 Claims. (Cl. 184—3)

This invention relates to the lubrication of rails which may be subjected to heavy loads, such as crane rails.

Rails and wheels of large travelling cranes are, during long travel movement, always subjected to lateral pressures which lead to considerable wear of rail and wheel flanges, resulting in lengthy and costly out-of-service periods of the crane necessitated by the carrying out of repairs.

By lubricating the rails with a lubricating oil dry friction between the rail and wheel flanges can be eliminated and wear and tear of the rail and wheel flanges consequently greatly reduced so that out-of-service periods of the crane are considerably curtailed or avoided.

In a known method of crane rail lubrication, a lubricating oil pump is driven automatically by the long travel of the crane, that is to say the pump operates only when the crane is travelling along the rails, which pump is connected by flexible piping to two crane rail applicators, one per rail. During travel of the crane the applicator applies the lubricant to the rail. The base plate of the applicator is mounted on an end of the crane end-carriage structure, below the buffer, on the centre-line of the rail. Attached to each base plate are two adjustable penduli each carrying a felt roller. Pressed against the rail flanges by their own weight and assisted by a tension spring, these felt rollers roll along the rail flanges, leaving a very thin oil film thereon which is constantly renewed. The lubricant is delivered to each applicator by the oil pump.

According to the present invention, a method of lubricating a desired portion of a rail for a travelling crane comprises rotationally sensing linear movement of the crane along the rail by frictional contact therewith and controlling the flow of a lubricant, such as lubricating oil, under gravity from a supply in response to said rotationally sensed movement by causing said rotationally sensed movement to open by centrifugal action a flow path from said supply to a desired portion of a wear-sustaining surface of the rail.

According to one aspect of this invention, a method of lubricating a rail for a travelling crane comprises establishing on the crane a supply of a lubricant, such as lubricating oil, in close proximity to the path of a rail relatively thereto, establishing a flow path between said supply and an upper portion of a wear-sustaining surface of the rail, rotationally sensing movement of the crane along the rail by frictional contact therewith and controlling the flow of lubricant under gravity from the supply in response to said rotationally sensed movement to permit lubricant to flow from the supply in the presence of such sensing movement.

According to another aspect of this invention, apparatus for applying a lubricant, such as lubricating oil, to a desired portion of a rail, such as a crane rail which can be subjected to heavy loads, comprises a rotatable vessel for receiving lubricant, a lubricant conveying roller connected to the base of the vessel for engagement with and applying lubricant to a desired portion of a side or flange

2

surface of a rail, means for mounting said vessel on a crane with its axis of rotation generally vertical or inclined from the vertical and with said lubricant conveying roller capable of engaging the rail on which the crane is carried and of imparting rotation to the vessel in response to motion of the crane along the rail, a flow passage between the base of the vessel and said roller for the flow of lubricant from within the vessel to said roller, and means responsive to rotation of the vessel about its axis of rotation for causing opening of said flow passage when the vessel is rotated.

Said means for causing opening of said flow passage may comprise a valve closure member, which normally rests on a seat to close the entrance to said flow passage, said seat having its axis eccentric to the axis of rotation of the vessel such that centrifugal action on rotation of the vessel causes the valve closure member to move off its seat to open said flow passage.

The base of said vessel containing the lubricant is preferably shaped as an inverted cone or a surface generated by the revolution of a curve about an axis, approximating to an inverted cone, with the axis of the inverted cone or said surface eccentric to the axis of rotation of the vessel. An opening in the base of the vessel for said flow passage is concentric with the axis of the inverted cone or said surface and said means responsive to rotation of the vessel about its axis of rotation may consist of a ball-shaped member which is automatically seated by its own weight on said opening when the crane is stationary. When the crane is in long travel motion, the lubricant-containing vessel is caused to rotate about its axis of rotation and resultant centrifugal force causes the ball-shaped member to ride up the inverted cone or said surface, thus uncovering said opening.

The lubricant-containing vessel forms part of an applicator which may be in the form of a pendulum of which one end is pivoted to the end carriage of the crane and the other end carries said lubricant conveying roller which presses against the rail, and the longitudinal axis of which is also the axis of rotation of said lubricant-containing vessel. The applicator may, however, be mounted on the crane structure by some other means such as, for example, an inclined slideway.

In a preferred apparatus the vessel containing the lubricant may consist of a cylindrical shell co-axial with the longitudinal axis of the pendulum, closed at its top by a detachably fastened cover plate and at its base by a detachably fastened piece which detachably carries said roller. The top cover plate of the said vessel may be integral with or rigidly fastened to a spindle rotatable inside a bearing box rigidly attached to a coupling member pivoted to the end carriage of a crane. The base piece of the said vessel is shaped to form the base of the vessel and is provided with an opening through which lubricant can pass to the said roller.

The said roller may consist of a number of circular felt discs concentric with the longitudinal axis of the pendulum and held together and detachably fastened, for example, by screwed studs or bolts, to said base piece, the discs being each provided with a hole concentric with the opening in the base piece and radial grooves on their mating surfaces communicating with the said hole, said grooves forming passages or ducts through which the lubricant is forced, by centrifugal force, from the said hole to the outer edge of the roller.

The top cover plate of the vessel containing the lubricant may be provided with a closeable connection through which the vessel may be periodically filled with the lubricant. Alternatively, a passage may be provided inside the pendulum member pivoted to the end carriage and the said passage connected by flexible pipe to a lubricant tank mounted on the long travel frame of the crane and an-

other passage provided inside the rotatable spindle and top cover plate of the said vessel, so that lubricant can pass from the said lubricant tank to the said vessel, the vessel and bearing box being maintained filled with the lubricant.

Two applicators are preferably provided for each rail on which the crane travels, the applicators pressing against opposite sides of the rail and being so oppositely inclined. Both applicators may be attached to the same end of the carriage, or one applicator may be attached to one end of the carriage and the other to the opposite end.

Any lateral movement of the crane chassis relative to the rails is compensated for by the penduli. By this means the rollers apply the lubricant only to the sides of the rails and never to the head of the rails.

An advantage of the method and apparatus of crane rail lubrication according to the present invention is that it does not need a pump for delivering lubricant to each applicator.

The invention will be further described with reference to the accompanying drawings which illustrate one embodiment of the invention, by way of example only, and in which:

Fig. 1 is a sectional elevation of a lubricant applicator with its roller shown pressed against a crane rail,

Fig. 2 is a diagrammatic elevation showing the applicator attached to a crane end-carriage,

Fig. 3 corresponds to the upper part of Fig. 1 and shows an alternative arrangement for the supply of lubricant to the applicator, and

Figs. 4 and 5 are detail views in section showing alternative forms of the base piece of the applicator.

In the drawings similar parts are designated by the same reference numerals.

Referring first more particularly to Fig. 1, the applicator comprises a coupling member or lug 1 having a bearing passage 2 and a base threaded to screw into a cylindrical bearing box 3 which has a spindle 4 journaled therein by ball bearings 6 fitted between the bearing box and the spindle. The upper end of the spindle 4 is threaded to receive locating nuts 5 whilst its lower end is integral with a cover plate 7 which has a lower reduced portion threaded to screw into the top end of a cylindrical vessel 8. A base piece 9 has an external wall threaded to screw into the bottom end of the cylindrical vessel 8 and is shaped to form the base thereof. The upper surface of base piece 9 is in the form of an inverted cone having its axis B-B eccentric to the longitudinal axis A-A of the spindle 4 and so of the vessel 8, which vessel is adapted to rotate about axis A-A and to swing about bearing passage 2. Extending through the base piece is a circular passage 10 which is concentric with the axis B-B. A soft metal joint ring 11 is interposed between the bottom end of the vessel 8 and the base piece 9. A ball-shaped member 12 is provided to seat on and cover the top end of passage 10. A lubricant-applying roller 13 is secured between the underside of the base piece 9 and a back plate 14 by means of screwed studs 15. The screwed studs 15 engage in screw-tapped holes spaced around a bottom flange 9a of base piece 9, the studs passing through respective distance sleeves 16 which extend through aligned holes in a number of circular discs 13a, 13b, 13c and 13d of felt or other like or equivalent material which constitute said lubricant-applying roller 13. It will be noted that the opposite ends of the distance sleeves 16 abut the base piece 9 and the back plate 14, thus preventing unwanted compression of the discs 13a-13d when the studs 15 are tightened. The circular discs 13a-13d are concentric with the axis A-A of the spindle 4 and, with the exception of the bottom one 13d, are each provided with a hole 17 concentric with the passage 10 in the base piece 9. The roller discs are also provided with radial grooves (not shown) in their mating surfaces and communicating with the aligned

holes 17. The top cover plate 7 of the vessel 8 is provided with a filling connection or passage 18 closeable by a cover piece 19.

As more clearly shown in Fig. 2, the coupling member 5 1 is pivoted by its bearing passage 2 to an end carriage 20 of a long travel frame of a crane so that the applicator forms a pendulum swingable about the axis A-A with the roller 13 maintained pressed against the adjacent side of a rail 21 under the weight of the pendulum. A 10 flanged wheel 22 of the crane is shown located on the rail.

The vessel 8 is filled with lubricating oil through the connection 18, the oil level when the vessel is full being indicated by the line 23 in Fig. 1. When the crane is 15 stationary the ball-shaped member 12 will be seated by its own weight on the top end of the passage 10, effectively covering this opening so that no oil can pass to the roller 13. When the crane is in long travel motion, the roller 13 causes the vessel 8 to rotate about the axis A-A and resultant centrifugal force causes the ball-shaped member 12 to travel up the surface of the inverted cone, thus uncovering the top opening of passage 10 and allowing oil to pass, via the aligned holes 17 and radial grooves in the component discs, to the periphery of the roller 20 13 and so to the side of the rail 21. Thus, the flow of oil 25 from the vessel 8 is effected partly by gravity and partly by capillarity, and it will be obvious that the rate of flow will be largely determined, *inter alia*, by the size of the passages 10, 17 and the radial grooves in the roller discs 30 13a-13d, as well as by the nature of the material used for these discs.

When the oil level 23 in the vessel 8 has dropped to near the commencement of the inverted conical base the vessel is refilled with oil through the connection 19.

Referring now to the modified arrangement of Fig. 3, the coupling member 1 is drilled to provide a passage 23 concentric with the axis A-A of the spindle 4 and communicating with the inside of the bearing box 3, and a passage 24 at right angles to and communicating with the 35 said passage 23 and with a pipe union connection 25 detachably secured to the member 1. The pipe union connection 25 is connected to a flexible pipe 26 which is connected to the bottom of an oil supply tank (not shown) mounted on the long travel frame of the crane. The spindle 4 and integral cover plate 7 are drilled to 40 provide an axial passage 27 which communicates at the top with the interior of the bearing box 3 and at the bottom with the interior of the vessel 8. In this arrangement, lubricating oil passes from the said oil tank mounted on the crane through the flexible pipe 26 and 45 communicating passages 24 and 23 to the interior of the bearing box 3 and from there through the spindle passage 27 to the vessel 8. It will be appreciated that since the bearing box 3 and vessel 8 are maintained filled 50 with oil, the ball bearings 6 are continuously lubricated. An oil sealing ring 28, against which the spindle 4 rotates, 55 is provided in the bottom of the bearing box 3 and a soft metal joint ring 29 is provided at the joint between the coupling member 1 and the top of the bearing box 3.

Referring now to the modifications of Figs. 4 and 5, the base piece 9 is shaped to form the base of the cylindrical vessel 8 in the form of a convex surface 9b (Fig. 4) or a concave surface 9c (Fig. 5) generated by the revolution of a curve about an axis, approximating to an inverted cone, with the axis B-B of said surface eccentric to the longitudinal axis A-A of the spindle 4 of the vessel 8. The opening 10 is disposed concentric with the axis B-B as in Fig. 1.

With the exception of the roller 13, the applicator is 60 preferably constructed of metal throughout.

Two applicators may be suspended on a crane, or the like, from a common pivot so that the respective rollers 65 13 press against opposite sides of the rail 21. Both applicators may be attached to the same end of the carriage

of the crane or one applicator may be attached to one end and the other to the opposite end.

I claim:

1. Apparatus for applying a lubricant to a desired portion of a crane-supporting rail which can be subjected to heavy loads, comprising a rotatable vessel for receiving a lubricant, a lubricant conveying roller connected to the base of the vessel for engagement with and applying lubricant to a desired portion of a side surface of a rail, means for mounting said vessel on a crane with its axis of rotation generally vertical and with said lubricant conveying roller capable of engaging the side surface of the rail on which the crane is carried and of imparting rotation to the vessel in response to motion of the crane along the rail, a flow passage between the base of the vessel and said roller for the flow of lubricant from within the vessel to said roller, said flow passage extending in a direction substantially parallel to the axis of rotation and terminating at its upper end in a valve seat having its axis eccentric to said axis of rotation, and a valve closure member co-operating with said valve seat and which normally rests upon said seat to close said flow passage and which is moved off said seat by centrifugal action upon rotation of said vessel about said axis of rotation.

2. Apparatus for applying a lubricant to a desired portion of a crane rail which can be subjected to heavy loads, comprising a rotatable vessel for receiving a lubricant, a lubricant conveying roller connected to the base of the vessel for engagement with and applying lubricant to a desired portion of a side or flange surface of a rail, means for mounting said vessel on a crane with its axis of rotation generally vertical or inclined from the vertical and with said lubricant conveying roller capable of engaging the rail on which the crane is carried and of imparting rotation to the vessel in response to motion of the

30

35

crane along the rail, said vessel having a generally cylindrical internal surface and a base member presenting inferiorly of said vessel a quasi-conical surface of which the axis is eccentric to the axis of said cylindrical surface, a flow passage extending through said base member of the vessel and communicating with the interior of said vessel and with said roller for the flow of lubricant from within the vessel to said roller, said flow passage extending in a generally vertical direction and terminating at its upper end substantially at the apex of said quasi-conical surface, and a ball shaped element co-operating with said base member and disposed within said vessel to rest substantially at the apex of said quasi-conical surface when said vessel is not rotating to close said flow passage and to be displaced under centrifugal action to open said flow passage when said vessel is rotating.

3. Apparatus according to claim 2 in which said quasi-conical surface is convex.

4. Apparatus according to claim 2 in which said quasi-conical surface is concave.

5. Apparatus according to claim 2 in which said quasi-conical surface is generated by the revolution of a curve about an axis eccentric to the axis of rotation of the vessel.

6. Apparatus according to claim 2 in which said flow passage has at its upper end a valve seat substantially co-axial with the axis of the quasi-conical surface.
